JAR-HOLDING DEVICE

Lee E. Mason, Columbus, Ohio

Application March 15, 1939, Serial No. 261,935

3 Claims. (Cl. 81—3.1)

My invention relates to a jar-holding device. It has to do, more particularly, with a device which is especially useful for holding food packing jars, such as glass Mason jars, hot or cold, during the application thereto and removal therefrom of screw caps, and the placing of cold jars in an oven, and the removal of the jars from the oven when hot, when canning, eliminating the danger of burning the hands, et cetera. However, it may also be used for other purposes.

In the past, there have been several different devices of the general type indicated proposed. However, these devices have not been very suitable and the result is that they have not gone into use to any appreciable extent. At the present time, it is the practice for housewives to use a towel in holding hot jars, which have been filled with food products, during the application of the caps thereto and during the removal of jars from an oven. Obviously, this method is not very satisfactory. The devices proposed in the past for holding jars have not been very practical and most of them have been of a complicated structure and expensive to manufacture.

One of the objects of my invention is to provide a jar-holding device of the type indicated which is very simple in structure so that it may be made and sold at a low price.

Another object of my invention is to provide a device which is not only simple and inexpensive but which is very effective, being of such a type that it will grip the jar firmly throughout the circumference thereof, so that a filled jar, whether hot or cold, may be lifted readily and placed in or removed from an oven and may be easily held while applying a cap thereto.

Various other objects will be apparent from the following description.

The preferred embodiment of my invention is illustrated in the accompanying drawing wherein in similar characters of reference designate correspondings parts and wherein:

Figure 1 is a perspective view of a jar-holding device made in accordance with my invention.

Figure 2 is a transverse section taken through the jar-gripping portion of the device.

Figure 3 is a plan view of the device shown in Figure 1 and indicating how it will be applied to a jar.

Figure 4 is a perspective view illustrating how the jar may be held with my device during the application of a cap thereto.

Figure 5 is a plan view of a slightly modified form of my device.

With reference to the drawing, I have illustrated my device as comprising a metallic member 1, a rubber member 2, and handle members 3 and 4. The metallic member 1 is preferably made of resilient metal and is of rectangular cross section substantially throughout its length. However, it may be of other angular cross section.

The member 1 is formed of a strip of metal which is bent into the shape illustrated in the drawing. It is bent to form a main substantially annular portion 5 having its end portions 6 and 7 spaced from each other. Connected to these end portions and forming continuations thereof, are spring loop portions 8 and 9 which are formed by bending the metal rearwardly substantially parallel to the portion 5 and then again forwardly substantially parallel to the portion 5, as indicated by the numerals 10 and 11. The portions 11 are continued to a point substantially in line with the end points 6 and 7 of the portions 5 and are then bent outwardly as at 11' to form handle-receiving portions 12 and 13 which are substantially parallel to each other. These portions 12 and 13 are preferably of circular cross section so that they will fit into the sockets 25 formed in the handle members 3 and 4.

The portion 5 of the member 1 is adapted to receive a rubber jar-gripping member 14. This member is in the form of a strip of rubber of substantially rectangular cross section. It has a socket 15 of rectangular cross section extending entirely therethrough and adapted to receive the portion 5 of the member 1. One wall of the member 14 is split throughout its length as at 16 so that the rubber member 14 may be slipped over the portion 5. The member 14 may have grooves and notches formed on its inner surface or may be provided with other types of rough surface so that it will more firmly grip the jar. However, the rough surface is not necessary since the rubber material will not readily slip on the jar. Instead of being rubber, the member 14 may be of any other suitable flexible friction material which will not slide on the jar. Although I prefer that the member be of the cross section shown, it is not necessary that it be of this shape.

In using my device, it is merely slipped downwardly over the jar as indicated in Figures 3 and 4. It will be normally expanded so that it will be spaced slightly from the jar throughout the greater portion of its circumference. To grip the jar, it is merely necessary to draw the handles 3 and 4 closer together. This will cause the end portions 6 and 7 of the member 5 to swing in-

wardly into contact with the surface of the jar. The provision of the spring loop portions 8 and 9 is very important. They serve as spring levers for causing the ends 6 and 7 of the portion 5 to move into contact with the jar and, as the pressure on the handle portions 3 and 4 is increased, the loop portions 8 and 9 will serve as levers for creating a pull or pressure on the ends 6 and 7 which will place the entire portion 5 under tension, drawing it tightly around the jar. Thus, the gripping action will take place substantially completely around the circumference of the jar and the gripping action will be uniform throughout the circumference. Without the spring loop portions 8 and 9, this would not take place.

It will be apparent from the preceding description that I have provided a device having many advantages. It is extremely simple but will grip the jar effectively substantially throughout its circumference. Since the rubber member 14 has a socket of rectangular cross section which cooperates with the metal portion 5 of rectangular cross section, the member 14 will not rotate on the portion 5. This rubber member may be replaced readily with a new member when it becomes worn.

In Figure 5, I have illustrated a slightly different form of my device. In this form, the ends 6a and 7a are spaced farther from each other and the loop portions 8a and 9a are formed at points spaced farther from the handles 3a and 4a.

Various other advantages will be apparent from the preceding description, the drawing and the following claims.

35. This device may also be used as a wrench for engaging and removing screw caps from jars and where I refer to a "jar-holding device" in the claims, I also intend to cover a cap-gripping device.

40. Having thus described my invention, what I claim is:

1. A jar-holding device of the type described comprising a metal member made of a strip of resilient metal consisting of a body portion of substantially annular form having ends spaced from each other, spring loop portions formed adjacent said ends, each of said spring loop portions consisting of a portion of said strip which extends rearwardly substantially parallel to the

body portion and then forwardly substantially parallel to said rearwardly extending portion, handle-receiving portions connected to the ends of said forwardly extending portions of said spring loop portions, handles on said handle-receiving portions which are substantially parallel to each other and which extend substantially at right angles to said forwardly extending portions of the loop portions, the body portion of said metal member being of substantially rectangular cross section, said body portion receiving a member formed of rubber which will contact with the jar and which has a socket of substantially rectangular cross section extending therethrough, one wall of said socket being split. 15

2. A jar-holding device of the type described comprising a metal member made of resilient metal consisting of a body portion of substantially annular form having ends spaced from each other, spring loop portions formed adjacent said ends, each of said spring loop portions consisting of a portion of said metal member which extends rearwardly substantially parallel to the body portion and then forwardly substantially parallel to said rearwardly extending portion, handle-receiving portions connected to the ends of said forwardly extending portions of said spring loop portions and having handles thereon, the body portions of said metal member being of angular cross section, said body portion receiving a member formed of rubber which will contact with the jar and which has a socket of similar cross sections extending therethrough. 25

3. A jar-holding device of the type described comprising a metal member made of resilient metal consisting of a body portion of substantially annular form having ends spaced from each other, spring loop portions formed adjacent said ends, each of said spring loop portions consisting of a portion of said metal member which extends rearwardly substantially parallel to the body portion and then forwardly substantially parallel to said rearwardly extending portion, handle-receiving portions connected to the ends of said forwardly extending portions of said spring loop portions and having handles thereon, said body portions having a non-metallic jar-contacting member disposed thereon. 30
